UNITED STATES PATENT OFFICE

ROY B. CULBERTSON, OF LA SALLE, COLORADO

ILLUMINATED TRAIN-ORDER HOOP

Application filed July 27, 1929. Serial No. 381,639.

This invention relates to improvements in train order hoops of the type employed for delivering orders to the engineer of a moving train.

In the operation of trains it is often times necessary to deliver orders to the engineer at stations where the train does not stop, and for this purpose it is customary to attach the orders to a hoop which is held in close proximity to the train so that the engineer or fireman, by extending his arm, may pass the arm through the hoop and thereby obtain possession of it and of the orders that are attached to it.

When train orders are to be delivered to a moving train at night it is obvious that this becomes very difficult owing to the fact that the engineer cannot see the hoop and therefore it frequently happens that he misses obtaining the order in which case it becomes necessary to stop the train, which entails considerable loss of time and expense.

It is the object of this invention to produce a hoop which shall be provided with an electric light that is illuminated when the hoop is in position to be used and which therefore makes it possible for the engineer to see the position of the hoop even on the darkest night, and by this means the danger of missing the hoop is almost entirely obviated.

It is another object of this invention to produce a hoop of the type referred to above which shall have a handle provided with a socket in which the hoop is removably held when in use and which therefore makes it easy to remove the hoop as compared with the present practice where the hoop is held in the hand of an attendant from which it must be removed by the use of considerable force.

The above and other objects that may become apparent as the description proceeds are attained by the means of a construction and an arrangement of parts that will now be described in detail, reference for this purpose being had to the accompanying drawing in which the preferred embodiment thereof has been illustrated and in which:

Fig. 1 is a side elevation of the improved hoop, parts thereof being broken away so as

to better disclose the construction and the battery casing being shown in section.

Fig. 2 is a section through the upper end of the battery casing and the socket and shows the lower end of the shank of the hoop in elevation, a portion of the shank being shown in section.

Fig. 3 is a transverse section through the shank, taken on line 3—3 Fig. 1.

Fig. 4 is a side elevation of the upper end of the hoop showing a slightly modified form of construction and

Fig. 5 is a section taken on line 5—5 Fig. 4.

In the drawing numeral 1 represents the straight shank of the hoop. The upper end of the shank has been curved so as to form a closed loop, or hoop, in the manner shown in Fig. 1. The end of the part forming the hoop is secured to the shank by means of a wire loop 2 or by any other suitable fastening device. The loop portion has been indicated by reference numeral 3. The hoop may be made from wood, from rubber composition or from any other suitable material. The material employed should be light and strong and should be able to withstand very severe usage. The lower end of the shank has secured to opposite sides thereof contacts 4 and 5, which are held in place by means of screws 6. Wires 7 each have one end connected with one of the contact plates, and extend upwardly along the outer surface of the hoop which is provided with grooves for the reception of these wires, in the manner shown in Fig. 3. Secured to the upper portion of the hoop is a metal casing 8, within which is located a lamp 9. The wires 7 are connected with the two terminals of this lamp, so that when a suitable source of electric current is connected with contacts 4 and 5 the lamp will be illuminated.

The housing 8 is held in place by means of screws 10 and is provided on opposite sides with openings 11, with which the lamp is in alignment, so that when the lamp is illuminated light will shine through openings 11 to both sides of the hoop and therefore the position of the hoop

can readily be determined on the darkest night.

For the purpose of attaching train orders to the hoop a spring 12 has been provided. 5 This spring has one end secured to the shank by means of screws or rivets 13, and its free end 14 rests against the side of the shank so that the train orders may be put into position between the spring and the shank 10 and will be held securely in place.

In order to make the lamp operate it is necessary to provide a source of electric current, and for this purpose I have provided two batteries 15 of the type employed 15 in connection with the ordinary flashlights. These batteries have a central terminal 16 at one end of the cylindrical wall, which forms the other terminals. For the purpose of holding the batteries I have provided a 20 casing 17 which is of the proper size to receive the batteries. The lower end of this casing is closed by means of a cover 18, and the top 19 is provided with a square socket 20. The metal of the casing and of the 25 socket is electrically connected with the cylindrical terminal of the battery. Secured to the inner surface of one side of the shank 20 is an insulating member 21. A spring 22 is secured to the socket and to the insulating member by means of rivets 23 that 30 are separated from the metal portion of the socket by means of insulating bushings 24, in the manner shown in Fig. 2. The upper end of spring 22 extends upwardly approximately to the upper end of the socket, and 35 rests against the inner surface of the insulating member. This spring is bowed inwardly in the manner shown. The lower end of spring 22 terminates in the upper 40 portion of the battery casing and has a transversely extending part 25 that is adapted to make electrical contact with the terminal 16 of the battery. When the shank of the hoop is put into position in the 45 socket in the manner shown in Fig. 1, one of the contacts, either 4 or 5, will come into electrical contact with the spring 22 and the other will be in electrical contact with the socket, and since the two batteries 15 are 50 connected in series between spring 22 and the socket 20, the voltage of these batteries will be connected across the lamp 9 and cause the latter to shine. The shank and socket are so proportioned that the hoop can be 55 readily removed from the socket, as there is no necessity for any great amount of friction as it is merely necessary to form such electrical contact between the socket and spring 22 and the contacts on the end of the 60 shank that current will flow to the lamp.

In Figs. 4 and 5 I have shown a modified form of construction. In the embodiment illustrated in these figures the metal housing 8 has been dispensed with, and the hoop has 65 been provided with a thickened portion 26

at its upper end. A hole 27 is bored diagonally inward from one side. This hole is of such size that it will receive the bulb 9 of the lamp. A socket 28 is secured in an extension of the hole 27 in the manner shown in Fig. 5. The socket is provided with the usual center and outside contacts to which the wires 7 are connected, and therefore when the lamp is in position in the socket and the shank is in position in socket 20, lamp 9 will be illuminated. The hoop is also provided with an opening 29 that permits light to shine through to the other side thereof. When the hoop is constructed in the manner shown in Figs. 4 and 5, the lamp is fully protected against injury and at the same time the lamp is visible from either side of the hoop.

With the parts constructed in the manner shown and described, let us assume that it is necessary to deliver a train order to the engineer of a moving train on a dark night. The order is put in place between the shank and spring 12, after which the end of the shank is put into the socket 20. As soon as the shank is introduced into socket 20, lamp 9 will be illuminated and will be visible through the openings 11 in the protecting casing 8, or through holes 27 and 29 if the construction shown in Figs. 4 and 5 is employed. The person who is to deliver the message grasps the casing 17 and holds the hoop in a position from which it can be reached by the engineer or the fireman on board the train. When the train approaches the engineer or fireman extends an arm through the hoop portion and carries the hoop and the orders away. After the orders have been removed, the hoop is thrown on the ground and is later picked up by some 100 of the station attendants.

From the above description it will be seen that I have produced a train order hoop, which in addition to the usual hoop construction, is provided with an incandescent lamp that is attached to the hoop portion, and I have also provided a battery casing having a socket which is adapted to receive the shank of the hoop, and to establish electrical connection between the batteries and the lamp.

In the construction shown and described, the lamp is surrounded by a guard that protects it against injury when it is thrown to the ground and when it is otherwise subjected to rough usage. Since the attendant, who is holding the train order hoop, uses the casing 17 as a handle, very little effort is necessary to remove the hoop and there is also no danger of the attendant being injured as sometimes happens when he holds the shank in his hand as the quickness with which the hoop is removed does not give him sufficient time to release his grasp with the result that injury sometimes is effected.

Having described the invention what I claim as new is:

5 1. A train order hoop having one end formed into a loop and the other comprising a straight shank portion, an incandescent lamp secured to the loop portion, electric contacts secured to the shank portion, a battery casing having a tubular socket attached thereto and adapted to receive the shank
10 portion and an insulated resilient contact located in the socket and adapted to cooperate with the contacts on the shank portion.

15 2. A train order hoop comprising in combination a closed loop having a straight shank extending from one side thereof, an incandescent lamp secured to the hoop portion, a guard enclosing the lamp, two electrical contacts secured to the shank and insulated from each other, electric conductors
20 extending between the contacts and the terminals of the lamp, a battery casing provided at one end with a tubular socket, said socket having two terminals, said terminals being electrically connected with terminals
25 of the batteries, and means for making electrical connection between the contacts on the shank and contacts in the socket.

30 3. In a train order hoop in combination a battery casing, batteries located within the casing, two spaced terminals carried by the casing, each of said terminals being electrically connected with one of the battery terminals, an incandescent lamp carried by the loop portion of the hoop, means carried by the hoop for making electrical connection between the lamp and terminals on the battery casing, and a guard for protecting the lamp against injury.

In testimony whereof I affix my signature.
40 ROY B. CULBERTSON.
